Primary Examiner — Leanne Was-Englehart

(57) **CLAIM**

The ornamental design for an access control device as shown and described.

DESCRIPTION

2.1 is a front, top, left-side perspective view of the access control device showing my new design;**2.2** is a front-side view thereof;**2.3** is a back-side view thereof;**2.4** is a left-side view thereof;**2.5** is a right-side view thereof;**2.6** is a top-side view thereof; and**2.7** is a bottom-side view thereof.

The broken lines depict portions of the access control device that form no part of the claimed design.
